UNITED STATES PATENT OFFICE.

PATRICK BERNARD DELANY, OF NEW YORK, N. Y.

TELEGRAPHY.

SPECIFICATION forming part of Letters Patent No. 373,967, dated November 29, 1887.

Application filed March 17, 1887. Serial No. 231,302. (No model.)

To all whom it may concern:

Be it known that I, PATRICK BERNARD DELANY, of New York, in the State of New York, have invented a certain new and useful Improved System of Telegraphic Transmission and Apparatus therefor, of which the following is a specification.

It is well known that in operating long lines, especially underground or submarine cables, the effect of the static charge is a serious obstacle in the way of rapid transmission, and that on this account the distance over which such lines can be operated is limited, and the speed of operation is necessarily slow. The best results heretofore obtainable on such lines have been secured by the use of reverse or alternating currents. Even the practice of this method, however, has been greatly impeded by the difficulties arising from the unequal duration of impulses sent into the line, and the consequent unequal static charge and discharge. It is well understood that when a dash is made the discharge of static is proportionally greater than when the dot is made, and that when a dot quickly follows a dash the effect of the discharge at the transmitting end is to partially neutralize or obliterate the dot, while at the receiving end the current "tails" or runs out of the line so slowly as to bridge over the space between the dash and the weakened dot which comes after it.

I am aware that in the automatic telegraphic system of Dr. Werner Siemens it has been proposed to employ perforated strips of paper for automatic transmission in connection with a magneto-generator, the speed or motion of the strip and of rotation of the generator being so regulated that the alternate generation of positive and negative currents shall coincide with the particular position of the perforation of the paper strip, and thereby, through suitable contacts, send into the line alternate currents of equal duration but opposite polarity, the impulses being received upon a suitable ink recorder having a polarized-magnet receiver.

I am also aware that signals which are received as dots and dashes have been transmitted by the use of two keys which send dots of alternating polarity; but with this system of working the duration of the impulses is necessarily of uncertain or imperfect uniformity,

and the operation of such a system requires specially-trained operators.

So far as I am aware, however, no system has heretofore been devised by means of which an ordinary Morse key may be manipulated to transmit dots and dashes by causing to be thrown upon the line impulses of electricity of alternating polarity and uniform duration.

The primary object of my invention is to provide such a new system involving the use of a Morse key. In my improvement, also, the line is put to earth and discharged after each impulse, so that succeeding impulses will not encounter even the weak discharge arising from a dot.

The invention also contemplates certain improvements in the manner of driving the apparatus, all of which fully appears from the following specification.

In the accompanying drawings, Figure 1 is a diagram view showing two connected stations organized for transmission according to my plan. Fig. 2 is a view of a single station, 75 showing a somewhat different arrangement for driving the apparatus; and Fig. 3 is a detail view showing another arrangement for driving the instrument.

Fig. 1 illustrates two stations, X and Y, and the organization is alike at each station. A Morse key, A, is connected with a local battery, L B, and both its front stop, c, and its rear stop, d, are connected with the opposite pole of the battery L B through the coil or 85 coils of a magnet, B. The armature-lever b of this magnet operates a push-arm, C, carrying a spring-pawl, e, which engages a ratchet, f, on a shaft carrying a trailing arm, G, similar to that of an ordinary sunflower in printing 90 telegraphy. This arm traverses and makes contact with a series of contacts, g h, each of said series being connected with one pole of a split main battery, M B, as clearly shown.

The main line M L is in electrical connection with the trailer by means of a brush, I I, which makes contact with the shaft or hub of the trailer. Between the contacts g h are arranged other, preferably smaller, contacts, l. As shown in the drawings, these contacts l are all part of an insulated plate, L, which is, by means of a wire, l', connected through the coils of a polarized relay, P R, to earth. The spring b² of the armature-lever normally tends to draw

the lever away from its magnet, and thus throw the pawl *e* out of engagement with the ratchet *f*. Whenever the key is closed either on its back or front stop, the lever is attracted and the pawl drives the ratchet and trailing arm *G* one tooth. In this movement the trailing finger *G* passes from a contact *l* across the face of a contact *h* or *g*, and then pauses upon the next contact *l*, as shown in the drawings. As the key is manipulated, therefore, the circuit of the magnet *B* will be completed at each contact *e* and *d*, and interrupted when the key is out of contact with both of them. By such an arrangement I obtain a rapid and regular rotation of the trailing finger.

From the construction shown it will be seen that when an instrument is receiving it is at rest, and the impulses from the line pass by way of brush *I*, insulated spindle, trailer, and insulated plate *L* to relay and earth. At the transmitter, as the trailer crosses an insulated battery, contact with the current passes from battery through contact, trailer, insulated spindle, and brush to line, and when the trailer pauses on a contact *l*, the battery now being disconnected from the line, the line is grounded through brush *I*, insulated spindle, trailer, insulated contact *l*, and relay.

Assuming that the operator at *X* is telegraphing to station *Y*, the Morse key *A* would, as will be obvious to anybody versed in telegraphy, be operated in the ordinary manner to produce dots and dashes. Thus when the key is pressed upon its front stop, *c*, the trailer would be moved across a contact *g*, thus sending a + current from the battery *M* to line, and at the station *Y*, through the brush *I*, plate *L*, and coil of polarized relay *P R*, to earth, thus actuating the relay in one direction and causing the operation of the sounder *S* in its local circuit. When the key is raised and then brought into contact with its back stop, *d*, the trailer is caused to pass over a contact *h*, thus sending a — current to the distant station, driving the armature of the polarized relay to its other stop, and terminating the signal there, whatever it be. Since the polarized-relay armature at the receiver remains in the position into which it is drawn by a transmitted impulse, whatever may be the polarity of the impulse, the character of the signal (whether a dot or a dash) depends upon the length of time during which the key is held down, the signal, whatever it is, being terminated when the key is put upon its back stop and a current of opposite polarity is sent into the line. Therefore, if the key be operated in the usual way, dots and dashes will be produced at the receiving end of the line; but the transmitted impulse is always of the same duration, because current only enters the line as the trailer at the transmitting-station crosses a battery-contact *g* or *h*. At the receiving-station the line is always to earth through the polarized relay, while at the sending-station, immediately after an impulse of either polarity

has been sent into the line, the line is grounded when the trailer *G* comes upon the contact *l* through the line *l* and coil of polarized relay *P R*. Obviously the alternating currents are thrown upon the line with perfect regularity, not in any manner dependent upon the touch of the operator. The operator by the manipulation of the key only decides whether the received signal shall be a dot or dash. The impulse sent must be invariably of the same duration. Of course, any receiving apparatus, instead of an ordinary sounder, *S*, may be employed in the local of the polarized relay. No switching or other changes for sending or receiving are required. When an operator is transmitting in the particular organization shown, his relay *P R* is not actuated by the current from the battery *MB*. The plates *L* being insulated, only the relay at the receiving station is actuated. This is an advantage, since it avoids the introduction of an unnecessary resistance at the transmitting-station, the stroke of the armature-lever of the actuating magnet *B* being entirely sufficient for the transmitting operator.

In Fig. 2 an arrangement for one station is shown identical in all respects with the arrangement in Fig. 1, except that, instead of employing a single driving magnet, *B*, two magnets, *B*² *B*³, are employed, being placed in branch circuits of a common local battery, *L B*. The branches are alternately closed as the key makes contact with its front stop, *e*, or its back stop, *d*. The movement of the trailer *G* and the operation of the apparatus are precisely the same; or, instead of the arrangement shown in Fig. 2, that illustrated in Fig. 3 may be adopted. In that figure the local battery *L B* is not split. One pole is connected through the coil of the magnet *B* with the front stop of the key, and the other connected directly with the key. In this arrangement the armature-lever *b* is bifurcated at its end, each bifurcation acting on the toothed wheel *f*—one of them when the key is closed and the lever *b* is drawn down by its magnet and the other when the key is open and the lever *b* is drawn up by its spring.

Since, so far as I am aware, I am the first to provide an arrangement for transmission by an ordinary Morse key in connection with an apparatus for throwing impulses of electricity of equal duration and alternating polarity upon the main line for producing either a dot or dash at the receiving-station, I do not limit myself to the precise organization shown, although it is a practical and efficient one.

I claim as my invention—

1. The combination, substantially as set forth, of a Morse key, apparatus for throwing working or message impulses of electricity of equal duration and alternating polarity upon the main line in response to the manipulation of the said key, and a polarized relay or receiving-magnet at the distant station for receiving the dots and dashes thus transmitted.

2. The combination, substantially as set forth, with a Morse key, a main line, and a source of electric energy, of a transmitter having contacts connected with opposite poles 5 of the source of energy, and a circuit-completer which traverses said contacts as the transmitter operates, and thereby throws upon the line working or message impulses of electricity of equal duration and alternate polarity, transmitter-controller devices interposed between the key and transmitter, whereby when the key is depressed the transmitter is actuated to send a current of one polarity, as described, and when the key is raised to transmit another current of equal duration but opposite polarity, and a receiver at the distant end of the line.

3. The combination of a Morse key, a rotating circuit-completer, electro-magnetic 20 driving devices and circuits interposed between the Morse key and rotating trailer, whereby the trailer is actuated, series of insulated contacts *g h*, arranged alternately with reference to each other, a transmitting battery 25 or generator having one pole connected to one series of contacts and the opposite pole connected to the other series of contacts, and a main line in electrical connection with the trailer.

3c 4. The combination of a main line, a rotating trailer in connection therewith, series of insulated contacts *g h*, arranged alternately with reference to each other, over which the trailer is caused to traverse, a transmitting 35 battery or generator having one pole connected with one series of said contacts and the other pole connected with the other series of said contacts, in combination with mechanism for rotating the trailer and transmitting dots 40 and dashes.

5. The combination of a main line and trailer in connection therewith, series of insulated contacts *g h*, arranged alternately with reference to each other, a main battery having one 45 pole connected to one of said series and the other pole to the other of said series, interposed contacts *l*, and a conductor, *l'*, connected with all of said contacts *l*, and running to earth through the coil of a polarized relay, 50 P R.

6. The combination of a main line with the following apparatus at each end thereof: a rotating trailer, with which it is in electrical connection, series of insulated contacts *g h*, 55 arranged alternately with reference to each other, over which the trailer is caused to traverse, a main battery or generator having one pole connected with one of said series and the other pole with the other of said series, contacts *l*, interposed between the other contacts *g h*, a line, *l'*, connected with the contacts *l* and running to earth through the coil of a receiving polarized relay, P R, and message-transmitting devices for rotating the trailer 65 step by step and at each actuation causing it to move from a contact *l* across the face of

an adjoining contact, *h* or *g*, and stop upon the next contact *l*.

7. The combination, with a main line and source of electric energy, of a Morse key, current-transmitting devices operated in response to the manipulation of the Morse key to throw upon the line intermittent electrical message impulses of equal duration and alternate polarity, receiving apparatus at the distant end 70 of the line for receiving such alternating equal impulses as dots or dashes, as set forth, and ground-connected contacts at the transmitting end of the line, with which the line is put in contact after each transmission of an impulse, 75 substantially as and for the purpose set forth.

8. The combination of series of contacts *g h*, a trailer, which traverses said contacts, a transmitting battery or generator having one pole connected with one of said series and the other pole with the opposite series, a Morse key, devices interposed between the Morse key and trailer for actuating the trailer by the manipulation of the key for the transmission of dots or dashes, polarized receiving apparatus at the distant station, through which the line is normally grounded and upon which the impulses are received as dots or dashes, as the case may be, and means at the transmitting-station for grounding the line after each 95 impulse has been sent into it.

9. The combination, with a table of insulated contacts, of a trailer which traverses said contacts, a Morse key, and devices interposed between the Morse key and the trailer, 100 whereby the latter is actuated step by step and caused to traverse the table of contacts, substantially as set forth.

10. The combination, with a Morse key, of duplicate magnets, a battery-circuit for each 105 of said magnets, connections whereby the circuit of one magnet is completed when the key is in one position and the circuit of the other magnet is completed when the key is in another position, the armature-levers of the magnets, a driven shaft, and lever-and-pawl mechanism, whereby the shaft is driven step by step as the magnets are alternately energized.

11. The combination, with a pivoted or vibrating circuit-interrupter, of electro-magnetic 115 actuating devices, a battery and circuit-connections, whereby said devices are energized or actuated when the vibrator is on either side of a central or neutral position, and mechanism which is driven step by step by said devices.

12. The combination of a Morse key, electro-magnetic actuating devices, a spindle driven thereby, a local battery, and circuit-connections between the battery, electro-magnetic devices, and key, whereby when the key is pressed upon its front stop the spindle is actuated one step, and when the key is raised from its front stop the spindle is actuated another step, substantially as set forth.

13. The combination of a main line, a contact, *g*, connected with one pole of a source of

electric energy, a contact, *h*, connected with an opposite pole of a source of electric energy, a trailer or circuit-completer traversing said contacts and connected with the line, a key, 5 devices interposed between the key and trailer, whereby the latter is actuated step by step as the key is manipulated and caused at each movement to cross the face of a contact *g* or *h*

and pause, and a receiver at the distant end of the line.

In testimony whereof I have hereunto subscribed my name.

PATRICK BERNARD DELANY.
